UNITED STATES PATENT OFFICE.

CHARLES R. MOELLENDORF, OF SEATTLE, WASHINGTON.

INCLOSED FUSE.

982,738.

Specification of Letters Patent. Patented Jan. 24, 1911.

Application filed July 18, 1910. Serial No. 572,553.

To all whom it may concern:

Be it known that I, CHARLES R. MOELLENDORF, a citizen of the United States, residing at Seattle, in the county of King and 5 State of Washington, have invented certain new and useful Improvements in Inclosed Fuses, of which the following is a specification.

This invention relates to improvements 10 in that class of electrical connections known as inclosed-fuses; and its object is the provision of a new and inexpensively constructed container for the fuse proper, said container being separable for conveniently 15 substituting a new fuse in place of one destroyed by being subjected to an excessive electric current.

The invention consists in the novel construction, and combination of devices, as 20 will be hereinafter described and claimed.

In the accompanying drawings, Figure 1 is a longitudinal vertical section of an inclosed fuse embodying my invention. Figs. 2 and 3, respectively, are underside and top 25 plan views of the upper and lower members of the fuse. Fig. 4 is a perspective view of one of the end elements such as employed in the member illustrated in Fig. 3.

The reference numerals 5 and 6 denote 30 complementary parts of a cylindrical or prismoidal shell composed of a suitable insulating material. The ends of said parts are respectively closed by complementary metallic cap elements 5' and 6' severally 35 provided with flanges 5'' and 6'' which overlie the peripheral surfaces of the respective shell parts to afford means whereby the cap elements may be fixedly secured to the shell parts by cementing 40 or otherwise. Integral with, or rigidly secured to, each of the cap elements 6' are inwardly and outwardly extending tongues 7 and 8. The outer tongues 8 are adapted to be secured to the terminals of the electric 45 circuit wires with which the fuse is to be applied. The inwardly directed tongues 7 are disposed to be in the plane of the edges of the shell part 6 which are juxtaposed with the other part when united. 50 Tongues 7 are provided with threaded apertures 9 for engagement with screws 10 whereby a strip 11 is detachably secured to such tongues. The strip which thus 55 serves to connect the tongues 7 is formed of a fusible metal or alloy. Within the spaces inclosed by the respective shell and

cap elements are packings 12 and 13 of asbestos or other refractory material, such as ordinarily employed with inclosed fuses.

From the foregoing, it is evident that 60 there is afforded two companion members each comprised of a casing and the packing therefor, and one of such members is further equipped with tongues which are utilized for the terminal and fusible strip connections. It is likewise evident that a fusible strip may be removed from its tongue connections by simply withdrawing the screws 10 and when another strip is substituted it may be as conveniently secured 70 by replacing the screws. The referred to members are separably united by headed screw bolts 14 passing through holes provided in the cap-flanges 5'' and the fillings thereof to engage in threaded holes 16 in 75 the cap-flanges 6''. The fuse device is thus seen to be readily dismembered or coupled and the replacement of a fusible plug will occupy but a little time.

The invention claimed, is—

1. An electrical fuse comprising complementary shell parts of insulating material, complementary cap elements of conducting material mounted upon the ends of the respective shell parts, a fusible element, 85 tongues extending inwardly and outwardly from the cap elements of one of said shell parts, means for detachably connecting said fusible element to the inwardly-extending tongues, and means extending through the 90 inwardly-extending tongues and the shell parts and their caps for detachably securing the said elements together.

2. An electrical fuse comprising complementary shell parts of insulating material, 95 complementary cap elements of conducting material mounted upon the ends of the respective shell parts, a fusible element, tongues extending inwardly and outwardly from the cap elements of one of said shell parts, means for detachably connecting said fusible element to the inwardly-extending tongues, means extending through the inwardly-extending tongues and the shell parts and their caps for detachably securing the said elements together, and a refractory filling for each of said shell parts.

3. An electrical fuse comprising complementary shell parts of insulating material, complementary cap elements of conducting 110 material mounted upon the ends of the respective shell parts, a fusible element,

tongues extending inwardly and outwardly from the cap elements of one of said shell parts, means for detachably connecting said fusible element to the inwardly-extending tongues, and means extending through the inwardly-extending tongues and the shell parts and their caps for detachably secur-

ing the said elements together, each of said inwardly-extending tongues gradually decreasing in width inwardly.

CHARLES R. MOELLENDORF.
